UNITED STATES PATENT OFFICE.

BYRON C. GOSS, OF CLEVELAND, OHIO.

CARTRIDGE CONTAINING GAS-GENERATING CHEMICAL.

Application filed March 29, 1926. Serial No. 98,270.

This invention relates to cartridges and the like for fire-arms containing gas-generating chemicals as the disabling agent, the gas being of that class which temporarily disables all persons within its sphere of influence, without causing permanent injury. 4 of mixed gas-generating chemical, and powder. Above the charge is a layer 5, of wad or the like, and above this is a film or layer 6 of a suitable water-proof material, such as wax, bakelite, varnish, etc. 60

An object of the invention is to provide a means whereby a quantity of the gas may be projected towards an object and gas 10 generated instantly, at a particular place, 65

A further object is to provide a cartridge containing a sufficient quantity of an immediately dispersable gas-generating chemical 15 associated with an igniting or heat and pressure generating explosive powder, such as black powder, smokeless powder, etc., and a suitable primer. 70

A further object is to provide a means whereby police officers and the like will be 20 enabled to temporarily disable groups of 75 criminals without exposing themselves to danger, the gas fumes from discharged cartridges spreading around corners in rooms, etc.

25 In the accompanying drawings:

Figure 1 illustrates in section a cartridge, a primer in the cap, and surrounded with a suitable propellant powder such as a layer of black powder, or smokeless powder, and 30 above this the charge of mixed powder and gas-generating chemical, the cartridges being suitably sealed;

Figure 2 illustrates in section a similar cartridge but with the mixed powder and 35 gas-generating chemical filling the entire cartridge, the powder being in increasing percentage around the primer;

Figure 3 illustrates in section a further modification in which the mixture is uniform throughout the cartridge, and in 40 which a larger primer is used;

Figure 4 illustrates in section a cartridge resembling Figure 1, except that the gas-generating chemical is not mixed with 45 powder; and

Figure 5 illustrates a cartridge generally similar to Figure 1, but containing a liquid charge instead of a solid charge of chemical.

50 In Figure 1, the cartridge shell 1 is provided with the usual primer 2, the latter projecting into a layer 3, of black powder, smokeless powder, or other suitable heat and pressure generating and igniting agent.

55 Above the layer of powder 3 is the charge

4 of mixed gas-generating chemical, and powder. Above the charge is a layer 5, of wad or the like, and above this is a film or layer 6 of a suitable water-proof material, such as wax, bakelite, varnish, etc. 60

The cartridge in Figure 2 resembles that in Figure 1, except that the gas-generating chemical is also mixed with the powder surrounding the primer, the percentage progressively decreasing from that in the 65 charge 8, above the primer, to practically zero, at the cap 9.

The cartridge in Figure 3 contains a uniform mixture of powder and gas-generating chemical 10, throughout; it may be provided with a longer primer 11, to ignite the 70 charge further in the cartridge.

The cartridge in Figure 4 contains powder 15, and a gas-generated chemical 16 in contact therewith but not mixed with powder. 75

The cartridges may be made in several sizes, to fit the standard sizes of small arms, and also shot-guns. The primer may be covered with black powder, or other powder, as illustrated in Figure 1, or with a graduated mixture of powder and chemical as in Figure 2, or with the charge mixture, as in Figure 3. 80

The charge mixture 4 may consist of one 85 part by weight of finely divided black powder to three parts by weight of a finely divided gas-generating chemical, for example, chloracetophenone, both thoroughly mixed to a uniform mixture. While this 90

percentage is preferred, the percent of black powder may vary between fifteen percent and 40 percent, without much change in efficiency. Instead of black powder, the 95

heating and igniting agent may consist of smokeless powder, as above noted, and the composition may vary from about ten percent smokeless powder and ninety percent gas-generating chemical to about ninety percent of smokeless powder and ten percent of gas-generating chemical.

100 Instead of the chloracetophenone, other gas-generating chemicals, either solids, or liquids, as at 12, Figure 5, separated from the black powder 13 by a wad 14, may be used. Such other chemicals are benzyl-

105

110

bromide, bromo-acetone, chloromethyl-chloroformate, etc. In the case of liquids the explosion of the powder generates sufficient heat and pressure to project, spray, and vaporize the liquid as it is discharged from the pistol, or gun, so that a mass of rapidly expanding vapor, like a cone of smoke and gas, leaves the gun, the liquid being volatilized by the heat generated by the combustion of the powder. In the case of solid chemicals the combustion of the intermixed powder through the charge raises the temperature of the chemical to the volatilizing point, so that it also is projected from the pistol as a cone shaped mass of rapidly expanding smoke and gas, in both cases, the generation of gas continuing after the charge leaves the pistol by the continued combustion of the powder. The expanding gas is projected a distance of from twenty to twenty-five feet from the pistol, and with larger cartridges may be projected still further. When a cartridge is shot into a room, or through a key hole, or under a door, or through any other crevice, the gas generating mixture with an explosive charge is projected into the exact space where we want the gas generated, the expanding gas rapidly filling every part of the room, making it unnecessary to aim the shot at any special object. The use of black powder generates smoke and indicates the direction and location of the gas. All persons in the room are at once temporarily disabled by the gas fumes, from which recovery takes place soon after leaving the gaseous atmosphere. If a person should be shot directly in the face with the gas, it is probable that instant blindness would result due to the extreme pain and irritation of the eyes, causing extreme, lachrymation, as well as sneezing and coughing. If shot into a room of twenty feet by twenty feet, (or even a much larger room) it would be impossible for some time for any one to enter or to remain in the room without being disabled by the fumes. After a lapse of a short period, persons equipped with gas masks may enter and capture disabled persons. The cartridges may be made in several sizes, and may be carried in the pocket by police, and others, for use in such pistols as they regularly carry.

As noted above, on the discharge, of a pistol loaded with one of the cartridges of this invention, the gas-generating chemical immediately begins to violently liberate gas and is at the same time instantly projected by the charge of powder to the desired objective, as in the case of a solid bullet, the chemical continuing to violently liberate the gas during its flight across the space, thereby leaving a trail locating its passage, and violently liberating the remainder of its gas upon its arrival at its objective.

Gas-generating devices in use at this time differ from my invention in that while some of them are mixed with powder, they are not capable of producing the same results. With the devices now in use the powder is for the purpose of generating sufficient heat to liberate the gas, the gas then diffusing through the atmosphere and slowly filling the room, while with my invention the gas-generating chemical is at the same time intensely heated to liberate gas and also instantly projected to the desired objective while gas is being violently liberated, the remaining gas being violently liberated at the objective. If two persons were on opposite sides of a room about twenty-five feet apart, one armed with my invention and the other armed with one of the known gas-generating devices now in use, and each "fired" the cartridge at a signal from an umpire, the one armed with my invention would instantly disable his opponent without discomfort to himself and would be able to leave the room safely before the gas from the opponent's cartridge spread across the room. The gas-generating chemical in my invention takes the place of a bullet in the cartridge with the further advantage of beginning the violent generation of gas while it is still in the barrel of the pistol, and continuing to violently discharge the gas until it is exhausted after reaching its objective.

Having thus described the invention, what is claimed is:—

1. A cartridge for fire-arms containing a primer, a propellant powder, and an immediately dispersable gas-generating chemical, said chemical arranged to be projected and immediately dispersed by the released energy of the propellant powder upon the firing of the cartridge.

2. A cartridge for small fire-arms containing a primer, a propellant powder adjacent said primer, a fuming, blinding, and disabling gas-generating chemical intimately mixed with a portion of said powder and in direct contact with the powder adjacent the primer, and a moisture-proof seal closing said cartridge.

3. A cartridge for small fire-arms containing a primer, a propellant powder adjacent said primer, a gas-generating chemical intimately mixed with a portion of said powder, and in direct contact with the powder adjacent the primer, said mixed gas-generating chemical and powder consisting of about three-fourths of chemical and one-fourth of powder, and a moisture-proof seal closing said cartridge.

4. A cartridge comprising chemical and sufficient explosive propelling powder for the violent generation and instant delivery of a fuming, blinding, and disabling gas in a dense state on a desired spot about

fifteen to twenty or more feet from the point of discharge when fired from a fire-arm, the charge in said cartridge starting the evolution of said fuming gas within 5 the fire-arm, and propelled to its objective while fuming by the associated propellant and completing the evolution of the fuming

gas at the objective, the transportation and delivery of said fuming gas at the objective being independent of external forces of air ¹⁰ currents or diffusion.

In testimony whereof I hereby affix my signature.

BYRON C. GOSS.
